UNITED STATES PATENT OFFICE.

ROBERT PRUE, OF MANSFIELD, MASSACHUSETTS.

ADJUSTABLE WINDOW-SHADE HANGER.

Application filed November 25, 1921. Serial No. 517,574.

To all whom it may concern:

Be it known that I, ROBERT PRUE, a citizen of the United States, residing at Mansfield, in the county of Bristol, and State of Massachusetts, have invented certain new and useful Improvements in Adjustable Window-Shade Hangers, of which the following is a specification.

The invention has reference to a window shade hanger and provides an adjustable type of hanger which can be adjusted prior to being made fast to a window casing to any size shade or window.

An additional object is to provide an adjustable type of shade hanger adapted to support a shade in such manner as to permit the latter to be taken off or put on without disturbing any part of the hanger, after it is fastened to the window casing 20 in its adjusted position.

An additional and further object of the invention is to provide an adjustable shade hanger having novel fastening means, embodying a hinge, one leaf of which is adapted to be swung back to fasten to the top or under side of window casing or left straight to fasten to the front face thereof as circumstances may require, it being therefore possible to make a suitable connection 30 with window casings of various types.

A further object of the invention is to provide a device of the above character that is simple in construction, strong and durable, and which it is believed may be manufactured at a reasonably low cost.

Various other objects and advantages of the invention will become apparent during the continuance of the following description.

40 In the drawings:

Figure 1 is a perspective view of the upper or top end of a window casing showing the manner of applying the invention thereto.

45 Figure 2 is a vertical cross section of the casing.

Figure 3 is a sectional view of the different types of casing showing the invention as fastened to the casings on the in- 50 side.

Figure 4 is a sectional view of still another type of casing and showing the invention as fastened to the top thereof.

55 The shade hanger comprises tubular sections 10 and 11 respectively flattened on opposite sides and slidable one within the

other as illustrated. By sliding section 11 inwardly of section 10, the length of the hanger may be decreased to a size suitable for windows of small width whereas by adjusting the section 11 outwardly of section 10 the length of the hanger may be increased to a size suitable for larger windows. The sections are normally held in their relatively adjusted positions by the 60 clamping or binding action of outer section 10. This section being provided on the inner side with a longitudinally extending central slot 12 which slot divides the inner side of the outer section into upper and 65 lower contracting portions 13 and 14.

Outer section 10 is preferably constructed of some springy material and is to be formed with a bore of such size as to cause the contracting portions 13 and 14 to be 70 slightly forced apart by the insertion of section 11. Consequently the two sections will be mutually held in an adjusted position by reason of their relatively frictional 75 engagement which will be sufficient to prevent the parts from accidentally slipping out of adjustment while being fastened to the window casing. Hanger section 10 is provided at its outer end with a shade bracket 15 having a slot 16 for the reception of one 80 end of a window shade. The other end of the shade is supported in a suitable bracket 17 carried at the outer end of inner section 11 and provided with a suitable opening 18.

These brackets are each integral with 90 their respective supporting sections and hence are movable to or from each other for fitting shades of various sizes.

The hanger is fastened to a window casing by suitable hanger supports such as indicated at 19. There are preferably two of such supports arranged one at each end of the hanger and fastened to the latter in proximity to a shade bracket. As shown in the drawing, the supports are preferably 95 in the form of hinges having a lower leaf 20 provided with a hook extension 21 adapted to hook under the hanger and soldered or otherwise made fast thereto. The upper hinge leaf 22 is provided with a suitable 100 number of openings to receive fastening screws 23 for fastening the support to a window casing, such as illustrated at 24. By reason of the upper hinge plates 22, the shade hanger can be suitably supported 105 from window casings of various types since these upper leaves can be readily swung to 110

a position permitting convenient attachment of the support to the casing. In other words, they may be turned back to fasten to top of window casing or the under side thereof as shown to advantage in Figures 3 and 4 of the drawings. Or, on the other hand, they may be left straight to fasten to the front face of the casing as shown in Figures 1 and 2. In either case, the shade hanger, it is to be noted is properly supported for holding the window shades in correct position and since the hanger sections are adjusted to the proper size prior to fastening the same to the window casing, it is obvious that there will be no disturbance of any part of the shade hanger after it is fastened in place.

From the foregoing it is believed that the advantages and novel features of the invention will be readily understood and therefore further detailed description is deemed unnecessary.

What is claimed is:—

1. An adjustable window shade hanger comprising a pair of telescopic, adjustable, hanger sections, a shade bracket at the outer end of each section and a hinged fastener associated with each hanger section, each hinge fastener having a lower leaf fastened to the section and its upper leaf movable for engagement with various sides of the casing and fastening means carried by the upper leaf.
2. An adjustable window shade hanger comprising a pair of tubular hanger sections relatively telescoped for slidable adjustment one within the other, the said outer section

being split longitudinally of one side to provide elastic clamping portions, frictionally gripping the inner member to hold the sections in adjusted relation, a hinge fastener for each section, each fastener having one leaf fastened to a section and its other leaf adapted for attachment to a window casing.

3. An adjustable window shade hanger comprising a pair of longitudinally slideable members telescoped at their inner ends and having right angularly disposed portions at their respective outer ends constituting shade brackets between which a shade roller is adapted to be supported and a hinged supporting element for each member, said elements respectively embodying a pair of vertically aligned plates relatively connected for movement about a horizontal pivot with the lower plate affixed to the member and the upper plate presenting means for attachment to a window casing or other support.

4. A hanger for window shade rollers comprising a pair of roller supporting brackets, carrier means extending between and connecting said brackets and designed to extend across practically the entire width of a window casing, and attaching plates permanently joined to the carrier means by a hinge connection permitting said plates to be selectively secured to either the vertical or horizontal surfaces of the upper transverse member of the aforesaid window casing.

In testimony whereof I affix my signature.

ROBERT PRUE.
